AIR HAMMER

Shigeru Yabe, Nishiyodogawaku, Osaka, Japan

Application March 15, 1937, Serial No. 131,112

5 Claims. (Cl. 78—42)

This invention relates to an air hammer.

In the air or pneumatic hammer hitherto known in which the piston in the compressing cylinder is reciprocated by the crank shaft revolved at the same speed during its whole stroke, the speed of the piston is contrarily retarded at the end of the up stroke when the highest compression is to be required, which results in the weakening of the hammering power. In the present invention these difficulties are completely removed by the rapid movement of the piston at the end of its up stroke, the hammering power being highly increased immediately before and after the hammering. The further advantage of the present invention consists in that a high hammering may be developed with a small type of the machine and the thinning of the material to be forged may be avoided, the undue cooling of the material being completely excluded.

According to this invention, the piston in the air compressing cylinder of air or pneumatic hammer is rapidly reciprocated at the end of its up stroke and the object of the invention is to provide an air hammer with a great hammering power.

In order that the invention may be clearly understood and readily carried into effect it will now be described by way of example with reference to the accompanying drawing, in which

Figure 1 is a side elevation of the air hammer partly in section.

Figure 2 is a front section of part of same.

Figures 3 and 4 being rough sketches showing the manner of working.

In the air compressing cylinder 1, the piston 2 is reciprocated and the air compressed is introduced into the hammering cylinder 3, so that the hammering rod 4 is moved up and down. In order to rapidly reciprocate the piston 2 at the end of its up stroke the elliptic toothed wheel 7 is keyed to the crank shaft 6 connected to the piston rod 5, said elliptic toothed wheel 7 being engaged with another elliptic toothed wheel 13 which has same major and minor axes keyed together with the flywheel 12 to the auxiliary shaft 11 revolved through the toothed wheels 9, 10 by the motor 8. The engagement of the elliptic toothed wheels 7 and 13 is made in such a manner that the minor-axial part of the former is in mesh with the major-axial part of the latter, when the piston is at the end of its up stroke.

In the present invention the speed of revolution of the crank shaft 6 is accelerated or retarded according as the major-axial part of the

eccentric wheel 13 is in mesh with the minor-axial part of the eccentric 7 or the minor-axial part of the former engages with the major-axial part of the latter, when the auxiliary shaft 11 is revolved with a given speed by the motor. Consequently, the speed of the piston reciprocating through the piston rod 5 by the revolution of the crank shaft is gradually accelerated in its up stroke, while it is gradually retarded in its down stroke. It is to be noted that the greatest power is required for hammering immediately before the hammering rod comes into contact with the anvil or when the piston in the compressing cylinder approaches the end of its up stroke. By rapidly reciprocating the piston near the end of the up stroke the air is highly compressed and the speed of the hammering rod largely accelerated, the hammering power being thus considerably increased. On the contrary, the speed of said rod is gradually retarded, when moved upwards. Immediately after the hammering, the rod quickly moves upwards so that the time of contact with the material to be forged is reduced to a minimum and cooling of the latter may be avoided completely.

What I claim is:

1. In a pneumatic hammer, the combination with a reciprocating hammer, a reciprocating pump and conduits cooperatively connecting the pump and hammer, of a power drive for said pump comprising, a driven shaft operatively connected thereto, a uniformly rotating driving shaft, a variable gear connection between said shafts, said gear connection causing said driven shaft to be driven at an increasing speed from the driving shaft through the upper portion of the stroke of the pump to increase the impact of the hammer upon the work.

2. In a pneumatic hammer, the combination with a reciprocating hammer, a reciprocating pump and conduits cooperatively connecting the pump and hammer, of a power drive for said pump comprising, a driven shaft operatively connected thereto, a uniformly rotating driving shaft, a gear connection comprising a variable radius gear on the driven shaft, and a variable radius gear on the driving shaft adapted to mesh with the variable radius gear on the driven shaft, said gear connection causing said driven shaft to be driven at an increasing speed from the driving shaft through the upper portion of the stroke to increase the impact of the hammer upon the work.

3. In a pneumatic hammer, the combination with a reciprocating hammer, a reciprocating

5 pump and conduits cooperatively connecting the
pump and hammer, of a power drive for said
pump comprising, a driven shaft operatively connected
to said pump, a uniformly rotating driving shaft, a gear connection comprising a spur gear fixed eccentric to the driven shaft and a
spur gear fixed eccentric to the driving shaft and in mesh with said first gear, said gear connection causing said driven shaft to be driven
10 at an increasing speed from the driving shaft through the upper portion of the stroke of the pump to increase the impact of the hammer upon the work.

15 4. In a pneumatic hammer, the combination
with a reciprocating hammer, a reciprocating
pump and conduits cooperatively connecting the
pump and hammer, of a power drive for said
pump comprising, a driven shaft operatively connected
20 to said pump, a uniformly rotating driving shaft, a gear connection between said shafts comprising, intermeshing gears having major and minor axial portions, said minor portion of the gear on the driven shaft being engageable

with the major portion of the driving gear to cause said driven shaft to be driven at an increasing speed by the driving shaft through the upper portion of the stroke of the pump to increase the impact of the hammer upon the work.

5 5. In a pneumatic hammer, the combination
with a reciprocating hammer, a reciprocating
pump and conduits cooperatively connecting the
pump and hammer, of a power drive for said
pump comprising, a driven shaft operatively connected
10 to said pump, a uniformly rotating driving shaft, a gear connection between said shafts comprising equal elliptic toothed wheels having major and minor axial portions, said minor portion of the wheel on the driven shaft being engageable with major portion of the driving wheel to cause said driven shaft to be driven at an increasing speed by the driving shaft through the upper portion of the stroke of the pump to increase the impact of the hammer upon
15 the work.
